UNITED STATES PATENT OFFICE

BLANCHE STINSON, ELISABETH SCHMIDT, MICHAEL MILOVICH, AND SOLOMON MILOVICH, OF SAN FRANCISCO, CALIFORNIA, ASSIGNORS TO MILO MANUFACTURING CO., OF SAN FRANCISCO, CALIFORNIA, A COPARTNERSHIP COMPOSED OF BORIS MILOVICH, MICHAEL MILOVICH, AND SOLOMON MILOVICH

DESIGN FOR A STUFFED TOY

Application filed August 8, 1930. Serial No. 36,611. Term of patent 7 years.

To all whom it may concern:

Be it known that we, BLANCHE STINSON, ELISABETH SCHMIDT, MICHAEL MILOVICH, and SOLOMON MILOVICH, citizens of the United States of America, residing in the city and county of San Francisco, State of California, have invented a new, original, and ornamental Design for a Stuffed Toy, of which the following is a specification, reference being had to the accompanying drawing, forming part thereof.

side elevation of a stuffed toy, embodying our invention.

We claim:

The ornamental design for a stuffed toy, substantially as shown.

In testimony whereof, we have hereunto set our hands.

BLANCHE STINSON.
ELISABETH SCHMIDT.
MICHAEL MILOVICH.
SOLOMON MILOVICH.
